UNITED STATES PATENT OFFICE.

HARRISON H. TAYLOR, OF DETROIT, MICHIGAN, ASSIGNOR TO THE DETROIT STEAM RADIATOR COMPANY, OF SAME PLACE.

MACHINE FOR ASSEMBLING RADIATOR-LOOPS.

SPECIFICATION forming part of Letters Patent No. 380,536, dated April 3, 1888.

Application filed December 7, 1887. Serial No. 257,257. (No model.)

To all whom it may concern:

Be it known that I, HARRISON H. TAYLOR, a citizen of the United States, residing at Detroit, county of Wayne, State of Michigan, have invented a certain new and useful Improvement in Machines for Assembling Radiator-Loops; and I declare the following to be a full, clear, and exact description of the same, such as will enable others skilled in the art to which it appertains to make and use the same, reference being had to the accompanying drawings, which form a part of this specification.

My invention consists of the combination of devices and appliances, hereinafter specified, and more particularly pointed out in the claims.

In the drawings, Figure 1 is a plan view of a machine embodying my invention. Fig. 2 is a side elevation of the same upon the side adjacent to the levers. Fig. 3 is an end view of the same adjacent to the gearing. Fig. 4 is a detail view of the ratchet mechanism for setting the radiator back to receive a new loop. Fig. 5 is a detail view of the chuck on a traveling carriage. Fig. 6 is a detail view of the chuck adjacent to the gearing. Fig. 7 is a face view of the arm which revolves the radiator-loop as it is screwed onto its seat. Fig. 8 is a view of the separating wedge-block.

It is the object of this invention to produce a machine which shall assemble the loops of a cast-iron radiator, the said radiator being of that type in which the loops are each provided with a hub at the base and are screwed each one to the adjacent one either directly or upon an interposed screw-threaded nipple.

This operation has heretofore been accomplished by hand, and has required very considerable time and labor and involved a corresponding expenditure.

In carrying out my invention, A is a suitable frame-work.

B is a chuck which is adapted to travel back and forth along the guide or way C. This traversing of the chuck may be effected in any convenient way. Thus, for instance, the pinion a may engage a rack-bar, A', on the side of the frame, so that by turning the pinion in one direction or the other the chuck to which

the pinion is journaled is caused to travel in a corresponding direction. The mechanism which I have employed for this purpose is illustrated in Figs. 2 and 4 of the drawings, in which a^2 is a lever journaled freely on the axis 55 of the pinion a . On the face of this lever is a pawl, a^3 , which engages the notch or ratchet wheel a^4 , fixed at the end of the pinion-shaft. This pawl is held in contact with the ratchet-wheel a^4 by a plunger, a^5 , and a spring, a^6 . 60 The pawl a^3 has two engaging-detents, so that it may operate the ratchet in either direction according as the one or the other detent is in contact with the ratchet.

a^7 is a pivoted dog on the side of the chuck 65 B, which may be thrown into engagement with the rack A', and so hold the chuck from any further motion in a direction away from the radiator. So, also, the particular detent on the pawl in contact with the ratchet-wheel will 70 depend upon the location of the point of the plunger a^5 with respect to the adjacent point of the pawl. This plunger a^5 may be brought to either position by simply pressing back its spring a^6 , as is clearly indicated in Fig. 4. 75

Through the chuck B passes freely a bolt, B', threaded at its extremity and of a size adapted to enter the tapped orifice in the hub of the adjacent radiator-loop. Such a radiator-loop is shown at D. 80

E is a stationary head or sleeve, in which is journaled the shaft E'. At one end of this shaft is fixed the lever E'', which engages each successive loop and revolves it about its hub as a center, so as to screw it to the adjacent 85 loop. On the other extremity of the shaft E' is the gear-wheel E''. This meshes with an elongated pinion, F, and by the intermediate gears, F' F'', the same is connected with the drive-shaft F', which is provided with fast and 90 loose pulleys F' and F'', respectively, a lever, F'', serving to operate the belt-shifter F', so as to throw the belt at will onto the tight or loose pulley, whereby the machine is thrown into or out of operation.

Returning now to the shaft E', this shaft is itself hollow, and through it passes a bolt, e, provided at its head with a crank to facilitate turning the same, and at its extremity the bolt is threaded, and is of a size to engage the 95 rco

threaded orifice in the hub of the loop D', which is to be connected into the radiator.

5 A lever, G, serves to operate a shifter, G', whereby the gear-wheel E³ is shifted in or out in a direction longitudinally of its axis.

The operation of the device will now be understood. The operator, wishing to assemble the loops into a radiator, takes the first loop, 10 places it on the frame of the machine in the position shown in Fig. 1 at D. He then runs the screw B' into its hub until he binds the said loop firmly against the chuck B. He then brings the lever or arm E² into the position shown in Fig. 1, and lays upon the lugs e² 15 the next loop D' with its hub opposite the extremity of the bolt e. This bolt is then screwed into the orifice in the loop until this loop is firmly bound against the face of the lever E². Then with the lever G the gear-wheel 20 E³ and its shaft E' are thrown forward, carrying the lever E² and its loop into proper position, so that the nipple d upon the loop D' will properly enter the adjacent hub. Then with the lever F⁶ the operator shifts the belt 25 from the loose pulley onto the tight pulley, the machine is at once set into operation, and the lever E², with its loop, is caused to revolve until the loop is screwed firmly to its seat.

30 H is a separating wedge-block, which is put over the last loop that is in position, so that when the next loop is screwed nearly home it may slightly deflect the same at its extremity, so that it will not strike against the loop that 35 has been already screwed down to its place. After this loop has been thus brought into its place the belt is again thrown onto the loose pulley, the bolt e is then run out from the hub 40 of the loop, and with the lever G the shaft E' and lever E² are again thrown back and a new loop is added, as before. This is continued until the loops are all assembled.

I would have it understood that this mechanism may be considerably varied without departing from my invention. Thus, for instance, other means might be employed for 45 communicating motion to the driving parts of the machine. So, again, the shaft E' and rotating lever E² might be arranged to be moved 50 axially forward and back without shifting the gear-wheel E³. So, also, any other convenient means might be employed for holding the loop D to the chuck B. So, also, other means might be employed for holding the loop D' to 55 the rotary lever E². In fact, the mechanism may dispense with any means for engaging the hub of the loop adjacent to said lever, and the machine is sometimes so employed. So, also, the chuck B might be simply a stationary support and the lever E² be caused to 60 recede as new loops are added until the loops have all been assembled. All changes of this character are within the province of an ordinary mechanic and would be what I would regard as equivalent constructions.

I am not aware that a machine was ever be-

fore made for assembling radiator-loops, but that heretofore they have always been assembled by hand.

What I therefore broadly claim is—

1. A machine for assembling radiator-loops, 70 consisting of a revolving lever or support with means for driving the same, said lever or support adapted to revolve about the axis of the hubs to be united as a center, and another support adapted to hold in proper position the loop or loops already assembled to which the new loop is to be applied, substantially as and for the purpose set forth.

2. In a machine for assembling radiator-loops, 80 the combination of a support for holding the first loop or loops to which the new loop is to be applied, a revolving lever or support for the loop to be applied, with means for revolving the same, and mechanism for causing one of said supports to approach the other, so as to engage the threads of the new loop with those loops already assembled, substantially as and for the purposes set forth.

3. In a machine for assembling radiator-loops, 90 a support adapted to hold the first loop, said support provided with means for moving it and its loop or loops to the rear to make place for new loops to be added, substantially as and for the purposes described.

4. In a machine for assembling radiator-loops, 95 a support for the first loop, provided with means for moving said support with its loop or loops to the rear to make place for new loops to be added, and in connection therewith mechanism for dogging said traveling support in any fixed position while the new loop is being added, substantially as and for the purposes described.

5. In a machine for assembling radiator-loops, 105 the combination, with a support for holding the first loop and a revolving support for the loop to be added, of centering mechanism whereby the hub of the first loop is held concentrically with the axis of the revolving support, substantially as and for the purpose set forth.

6. In a machine for assembling radiator-loops, 115 a support for holding the first loop and a bolt for simultaneously clamping the loop to its support and centering its hub, substantially as and for the purposes described.

7. In a machine for assembling radiator-loops, 120 a support for the loops already assembled, in combination with a revolving lever or support for the loop to be added, and mechanism for centering said last-named loop upon its support, substantially as and for the purposes described.

8. In a machine for assembling radiator-loops, 125 a revolving lever or support for the loop to be added, mechanism for driving the same, and a central bolt adapted to enter the hub of the loop and center it, substantially as and for the purposes described.

9. In a machine for assembling radiator-loops, 130 a revolving support for the loop to be

added, said support provided with means for engaging and holding the said loop and means for feeding it forward as it is engaged with and screwed upon the loops already assembled, 5 substantially as and for the purposes described.

10. In a machine for assembling radiator loops, a traveling support for holding the first loops and the loops already assembled, with mechanism adapted to move said assembled loops to the rear to make place for a new loop, and in combination therewith a revolving support for the loop to be added, means for engaging and centering the new loop thereon, and 15 mechanism for moving said support toward the assembled loops, whereby the threads of the new loop are engaged therewith, substantially as and for the purposes described.

11. The combination, with a support for the 20 assembled loops, of a revolving lever or support for the loop to be added, and a separating wedge-block adapted to rest upon the last loop

and ward off from contact therewith the new loop to be applied, substantially as described.

12. The combination of the revolving lever 25 E' with means for holding and centering a loop thereon, of a supporting-shaft, E', a driving-gear, E'', and a lever, G, adapted to shift the said shaft longitudinally of its axis, substantially as and for the purposes described. 30

13. The combination, with a traveling support, B, of a pinion, a, engaged with a rack-bar, A', and a lever, pawl, and ratchet for revolving the shaft of the said pinion and causing the support to traverse back and forth 35 along the ratchet-bar, substantially as and for the purposes set forth.

In testimony whereof I sign this specification in the presence of two witnesses.

HARRISON H. TAYLOR.
